UNITED STATES PATENT OFFICE.

WILLIAM O. OLSON, OF CHICAGO, ILLINOIS, ASSIGNOR TO THE MARMON CHICAGO COMPANY, OF CHICAGO, ILLINOIS, A CORPORATION OF ILLINOIS.

SPARK-PLUG.

1,335,793.

Specification of Letters Patent. Patented Apr. 6, 1920.

Application filed December 16, 1918. Serial No. 266,845.

To all whom it may concern:

Be it known that I, WILLIAM O. OLSON, a citizen of the United States, residing at Chicago, in the county of Cook and State of Illinois, have invented certain new and useful Improvements in Spark-Plugs, of which the following is a specification.

This invention relates to spark plugs for internal combustion engines and its object is to provide an improved plug which will produce a ribbon-like spark of full intensity and insure ignition of the maximum quantity of gas particles in the cylinder even under adverse conditions.

15 I have found that to secure satisfactory results with the low grade of gasolene now supplied the market for automobile and other gas engines, it is essential that the electrode terminals of the spark plug should be

20 maintained in a highly heated or substantially incandescent condition, and it is an object of my invention to provide a spark plug which will meet these requirements and produce an extremely hot and expansive spark

25 to insure the ignition which low grade gasolene requires.

It is also the object of my invention to provide an improved spark plug which will not become foul with carbon due to the presence 30 of oil in the cylinder but which will produce a spark so hot and so expansive that the oil will be entirely consumed and the terminals maintained in a clean condition.

In the accompanying drawings illustrating a preferred embodiment of the invention—

Figure 1 is a central sectional elevation of the spark plug;

Fig. 2 is a similar view of the insulating 40 core; and

Figs. 3-7 are detail views of the broad terminal.

Referring to the drawings, 7 is a shell having a reduced threaded neck 8 adapted for 45 insertion in the head of an internal combustion engine cylinder and provided with a shoulder or seat 9 to receive the gasket 10. The insulating core 11, preferably made of porcelain, has a shoulder 12 which engages 50 the gasket and the core and shell are held in assembled relation by the threaded sleeve 13, the lower edge of which engages a suitable packing ring 14. The core has a central bore 15 which is flared somewhat at its 55 upper end 16 and at its lower end 17 where

it opens into the chamber 18, this chamber extending from the lower end of the core to a point somewhat above the shoulder 12. This chamber provides the core with a comparatively thin petticoat 19 of more than 60 usual length.

An electrode 20, consisting of a straight rod, preferably round, having a flange 21, is arranged in the bore 15 and chamber 18 with its flange seated against a cement filling 22 in the flared lower end of the bore. The flared upper end of the bore is likewise filled 65 with cement to seal the dry air space of the bore between the electrode and the core. This electrode is held in assembled relation with 70 the core by a nut 23 between which and the end of the core are disposed one or more washers 24. The nut and washers are covered by a cap 25 and a terminal nut 26 is mounted upon the electrode above the cap. 75 This cap protects the core from the socket wrenches which are customarily used in tightening the spark plug in the engine and in removing it therefrom.

The electrode 27, which is suitably fastened to the shell 9, is provided with an enlarged flat terminal 28 having a long flat edge 29, which is disposed at one side of the terminal 30 of the electrode 20 and extends upward from the lower end thereof and in 80 parallel relation thereto. This terminal 28 is preferably provided with an opening 31 which may be of any suitable form, several of which are indicated in Figs. 1, 3, 4 and 5. The purpose of this opening is to reduce the 85 quantity of metal in the terminal so that it will heat more rapidly and to a higher degree. The lower edge 32 of the terminal 28 is preferably inclined downward and rearward from the straight front edge 29 to the 90 upwardly inclined rear edge 33 to form, in effect, a point 34 constituting the lowest part of the terminal, as shown in Figs. 1, 3 and 4, and in the slightly different forms shown in Figs. 5 and 7.

My improved spark plug has been found in practice to produce a broad ribbon-like spark of sufficient intensity to ignite the entire charge of gasolene in the cylinder and to provide complete combustion for any oil 105 that may be present in the cylinder and which would otherwise carbonize on and foul the terminals in a familiar manner. The size and intensity of the spark is such that the electrodes are quickly raised to substan- 110

5 tial incandescence which will preclude the accumulation of carbon thereon. The petticoat permits a considerable part of the explosion to take place in the chamber well up
 10 in the core and this not only keeps the chamber free from carbon but also provides for a high degree of heat which is desirable in meeting the conditions produced by low grade gasoline, or oil, or both. The hole 31
 15 in the broad terminal not only reduces the metal so that the terminal will heat up more quickly, but it also provides an opening through which the explosion gases will pass which tends to prevent the accumulation of
 20 carbon on the terminal. I prefer to stamp the electrode 27 out of a sheet of manganese nickel to secure the best results, but other materials may be employed as found desirable.
 25 20 Practical commercial use of my improved spark plug has demonstrated marked superiority over those spark plugs now in general commercial use because it provides a larger, hotter spark, like a ribbon or flame,
 30 25 because it quickly heats the terminals to a high degree, and because it provides for the entire combustion of oil and therefore maintains the terminals in a clean condition. I have found that it works with a
 35 30 high degree of efficiency in the lowest commercial grades of gasoline, that it enables the engine to be throttled to very low speed and permits fast acceleration, that it keeps the electrodes clean and free from the accumulation of carbon, and that it will operate satisfactorily in a cylinder which is passing oil badly.

40 In the drawings I have illustrated that form of my invention which I now consider to be the preferred embodiment thereof but I know that various changes in the form, construction and arrangement of parts may be made without departing from the spirit or sacrificing the advantages of the invention, and I reserve the right to make all such changes as fairly fall within the scope of the appended claims.

45 I claim:

- 50 1. A spark plug having two electrodes, the terminal of one of said electrodes having an extended edge arranged alongside and parallel with the terminal of the other electrode and a transverse opening adjacent said edge.
- 55 2. A spark plug having two electrodes, the terminal of one of said electrodes having a round surface and the terminal of the other electrode having an extended flat edge arranged alongside and parallel with
 60 said round surface and also having a transverse opening adjacent said edge.
3. A spark plug having two electrodes, the terminal of one of said electrodes being in the form of a straight rod and the termi-

65 nal of the other electrode being flat and arranged edgewise to provide a comparatively narrow and extended sparking edge alongside and parallel with the rod terminal.

4. A spark plug having two electrodes, the terminal of one of said electrodes being 70 in the form of a straight rod and the terminal of the other electrode being flat and arranged edgewise to provide a comparatively narrow and extended sparking edge alongside and parallel with the rod terminal, 75 said flat terminal having a transverse opening therein adjacent to said extended edge.

5. An electrode for a spark plug having a terminal provided with an extended sparking 80 edge and a transverse opening extending through the terminal and located back of and adjacent said edge.

6. An electrode for a spark plug having a flat angularly shaped terminal provided 85 with a straight extended sparking edge and a transverse opening back of an adjacent said edge.

7. An electrode for a spark plug having a terminal stamped from a flat metal sheet 90 and provided with an extended edge to be arranged in juxtaposition to another terminal and also having bottom and back edges downwardly inclined and meeting at a substantial point at the lowest part of the 95 terminal.

8. An electrode for a spark plug having a terminal stamped from a flat metal sheet and provided with an extended edge to be arranged in juxtaposition to another terminal 100 and having an opening back of said edge.

9. A spark plug having two electrodes, the terminal of one of said electrodes being in the form of a straight round rod, and 105 the terminal of the other electrode being stamped from a flat metal sheet and having an extended edge arranged alongside and parallel with said first-mentioned terminal and also having an opening back of said 110 edge.

10. An electrode for a spark plug having a flat angularly shaped terminal, the widest part of which is at its sparking edge, and a transverse opening back of said edge. 115

11. A spark plug having two electrodes, the terminal of one of said electrodes having two angularly disposed straight edges meeting at a point of convergence at the extreme bottom of said terminal and removed from the terminal of the other electrodes, and also having a transverse opening between its end and the point of convergence of said edges. 120
